(57) **CLAIM**

The ornamental design for a stand for desktop phone, as shown and described.

DESCRIPTION

FIG. 1 is a front, right perspective view of the stand for desktop phone showing my new design;

FIG. 2 is a front, right perspective view of the stand for desktop phone in an alternate position;

FIG. 3 is a front, right perspective view of the stand bracket for desktop phone showing my new design;

FIG. 4 is a front side view thereof;

FIG. 5 is a back side view thereof;

FIG. 6 is a left side view thereof;

FIG. 7 is a right side view thereof;

FIG. 8 is a top view thereof; and,

FIG. 9 is a bottom view thereof.

The broken lines are for illustrative purposes only and form no part of the claimed design.
